UNITED STATES PATENT OFFICE

148,795

DESIGN FOR A SINK

Leonard Keller, Tuckahoe, N. Y., assignor to
Borg-Warner Corporation, Chicago, Ill., a corporation of Illinois

Application January 19, 1946, Serial No. 125,757

Term of patent 14 years

(Cl. D4—2)

To all whom it may concern:

Be it known that I, Leonard Keller, a citizen of the United States of America and a resident of Tuckahoe, in the county of Westchester and State of New York, have invented a certain new, original, and ornamental Design for a Sink of which the following is a specification, reference being made to the accompanying drawing, forming a part thereof, in which:

Fig. 1 is a front perspective view of a sink, showing my new design;

Fig. 2 is a longitudinal sectional view taken along the plane of line 2—2 on Fig. 1; and

Fig. 3 is a transverse sectional view taken along the plane of line 3—3 on Fig. 1.

The essential features of my new design reside

in the portions shown in full lines on the drawings.

I claim:

The ornamental design for a sink, as shown and described.

LEONARD KELLER.
